(57) **CLAIM**

The ornamental design for an airbrush system, as shown and described.

DESCRIPTION

FIG. 1 is a perspective view of an embodiment of an airbrush system showing my new design;

FIG. 2 is another perspective view of an embodiment of an airbrush system showing my new design;

FIG. 3 is a front view of the airbrush system of FIG. 2;

FIG. 4 is a rear view of the airbrush system of FIG. 2;

FIG. 5 is a left side view of the airbrush system of FIG. 2;

FIG. 6 is a right side view of the airbrush system of FIG. 2;

FIG. 7 is a top plan view of the airbrush system of FIG. 2; and,

FIG. 8 is a bottom plan view of the airbrush system of FIG. 2.

The portion(s) of the airbrush system shown in broken lines are for environmental purposes only and do not form part of the claimed design.

1 Claim, 8 Drawing Sheets
